DRAIN

Clifford M. Rice, Alexandria, Va.

Application January 22, 1945, Serial No. 573,902

1 Claim. (Cl. 103—26)

1 The instant invention relates to shower bath drains and more particularly to such a drain for residential coaches, buses, trailers, trains, boats and the like.

One of the primary objects of the invention is the construction of a drain of the character indicated which automatically pumps the waste water into a waste storage tank.

Still another purpose is the construction of a shower bath drain having float-operated pump means within the drain pipe for automatically operating the pump when the float is raised by waste water flowing into said drain pipe.

The above and other aims and objects will be apparent from the detailed description herein-after appearing when taken in conjunction with the appended drawings to which reference is now made and in which the single figure is a vertical sectional view through a shower bath drain showing the invention.

As is well known, buses, coaches, trailers and the like, do not have the advantage of a long gravity flow in their shower or kitchen sink drain pipes. Accordingly, it is highly desirable that waste water be quickly removed and preferably by some automatically actuated mechanical means. This is accomplished in a simple and efficient manner by the construction illustrated on the accompanying drawing.

The reference numeral 1 designates the floor of a shower bath stall or alternatively the floor of a sink or bathtub. The well-known circular perforated plate 2 covers the opening 3 in the floor 1, said opening leading to a hollow drain pipe 4. Positioned within the hollow pipe 4 adjacent the perforated plate 2 is a float member 5 having an arm 6 extending from one side face thereof as at 7. The arm 6 projects into a hollow housing 8 integral with pipe 4. A pivot pin 9 is fixed transversely in housing 8 and pivotally supports arm 6 and an externally projecting arm portion 10 integral with arm 6. The arm 10 terminates in a contact member 11 connected to one pole of a source of electrical energy such as a battery or the like.

Hollow drain pipe 4 is further provided with a structurally integral bearing portion 12 for supporting the power shaft 13 of an electric motor M having a contact portion 15 positioned below contact member 11. As shown, contact member 15 is electrically connected to the other pole of the source of electrical energy aforementioned. The bearing member 12 is externally threaded at its outer end as at 16 for receiving internally threaded cap member 17 having packing mate-

rial 18 surrounding motor shaft 13. It will now be seen that bearing member 12 and shaft 13 are rendered leak-proof by means of the packing and the cap referred to above.

2 Shaft member 13 extends into drain pipe 4, the inwardly projecting portion having a crank 19 secured thereto for rotation therewith. A connecting rod 20 is pivotally connected to crank 19 as at 21, the other end of the rod 20 being pivotally connected to the cross bar 22 of a hollow cylindrical pump piston member 23 as at 24. As will be seen hollow pump piston member 23 is open at its upper end and is provided with a bottom wall 24 centrally apertured as at 25. A valve seat member 26 is internally secured to hollow piston member 23 and extends diametrically from opposed inner wall portions of member 23. It will be noted that seat 26 is positioned adjacent opening 25 and is provided with a hollow bearing 27. Extending axially through an opening 28 in bearing member 27 is a valve stem 29 having a valve cap or head 30 normally seated in and closing opening 25 in the wall 24 of piston member 23. A coil spring 31 surrounds the upper end of valve stem 29, one end of spring 31 circumferentially embracing bearing member 27. The upper end of valve stem 29 is threaded as at 32 and receives washer 33 and nut 34, the upper end of the coil spring 31 bearing against the under side of washer 33. It will be understood that the tension of spring 31 may be varied by adjusting the position of nut 34 on the threaded end 32 of valve stem 29.

In the position of the parts shown in the drawing the float member 5 floats on the surface of the water in the drain pipe 4 and contacts 11 and 15 are in non-contacting position. When waste water flows through apertured drain plate 2 into drain pipe 4 the float member 5 is raised with movement of rod members 6 and 10 about pivot pin 9. This brings about contact of members 11 and 15 with a consequent starting of the motor M. Motor shaft 13 is now rotated and with it crank arm 19, connecting rod 20, and reciprocatory movement is imparted to piston member 23. Upward movement of piston member 23 results in unseating of valve cap member 30 and the flow of waste water through opening 25 in the bottom wall 24 of piston pump member 23. Downward movement of piston pump member 23 results in closing of opening 25 and forcing of the waste water outwardly in horizontal extension 4a of drain pipe 4, said extension being preferably connected to a waste storage tank (not shown). The tension of spring 31 is so adjusted as to normally seat cap 30 of the valve on bottom wall 24.

of piston member 23 to close opening 25 therein. However, upward movement of the piston member 23 will unseat the cap 30 in the manner just described.

It will now be understood that operation of the motor continues as long as water is flowing into drain pipe 4 and is forced out of the pipe by action of piston pump member 23. When waste water no longer flows into drain pipe 4 the level of the float is lowered to assume the position shown in the single figure of the drawing with the consequent breaking of contact between members 11 and 15 and as a result the motor stops.

From the above it will be apparent that there has been constructed a device well adapted to perform its intended function. Various changes will be apparent to those skilled in the art to which this invention appertains and it is contemplated to cover all such and to be limited in this respect only as may be necessary by the scope of the claim hereto appended.

What I claim and desire to secure by Letters Patent is:

A vertically disposed drain comprising a hollow drain pipe, a substantially horizontally extending arm pivotally secured substantially centrally thereof to said pipe adjacent the upper end of the latter, one end portion of said arm project-

ing through and into the pipe and the other end portion projecting externally thereof, a float secured to the end of the inwardly projecting portion of the arm and an electrical contact secured to the end of the outwardly projecting portion of the arm, a motor supported by said pipe externally thereof and having an electrical contact member below and spaced from said float contact member, said motor having a shaft substantially parallel with said arm extending through and into the pipe, and a pump member within said pipe connected to and operated by said motor shaft upon closing of said electrical contacts.
